UNITED STATES PATENT OFFICE.

SAMUEL BLACHER, OF PROVIDENCE, RHODE ISLAND, ASSIGNOR TO JOSEPH E. MILLER, INCORPORATED, OF PROVIDENCE, RHODE ISLAND, A CORPORATION OF RHODE ISLAND.

COLLAR BUTTON.

1,414,617.

Specification of Letters Patent. Patented May 2, 1922.

Application filed September 6, 1921. Serial No. 498,770.

To all whom it may concern:

Be it known that I, SAMUEL BLACHER, a citizen of the United States, residing at Providence, in the county of Providence, State of Rhode Island, have invented certain new and useful Improvements in Collar Buttons, of which the following is a specification.

My invention relates to collar-buttons and particularly to buttons of the "lever" type for use in the neckbands of shirts and other articles of apparel.

The principal object of the invention is to provide a collar-button of the class described having a folding clamp or lever for insertion through the button-holes of the garments and adapted to close flat against the neckband to prevent it from catching or interfering with the other articles of apparel and from causing the coat-collar to bulge or bunch.

One object of the improvement is to provide a collar-button of simplified construction having a minimum number of parts adapted for economical manufacture from sheet-metal.

Another object of the improvement is to provide a button in which the parts may be more easily and quickly assembled, and having a structure which is more durable in use.

Further objects of the improvement are set forth in the following specification which describes a preferred embodiment of the invention as illustrated by the accompanying drawings.

In the drawings:

Fig. 1 is a perspective view of the complete button showing its lever or clamp in open position;

Fig. 2, a vertical sectional view of the same taken on the line 2—2 of Fig. 1;

Fig. 3, a similar view showing the lever closed;

Fig. 4, a perspective view of the saucer-like shell or back of the button;

Fig. 5, a perspective view of the resilient disk or spring-plate of the button;

Fig. 6, a plan view of the hinge-plate therefor;

Fig. 7, a sectional view of the same taken on the line 7—7 of Fig. 6; and

Fig. 8, a perspective view of the lever or clamp-member of the button.

55 In general my improved collar-button

comprises four co-operating elements: a cupped shell or back 3; a hinge-plate 4 secured within the rolled rim of the shell; a lever or clamp-member 5 pivoted on the hinge-plate 4; and a disk-like washer or 60 spring-plate 6 arranged beneath the hinge-plate 4 and adapted to act on the lever 5 to hold the latter in either opened or closed position.

All of the several parts of the button are 65 preferably stamped from sheet-metal and formed to the required shape in suitable dies operated in a stamp or punch-press. Referring to Fig. 4, the main shell or back 3 of the button is constructed from a circular blank which has its edge bent upwardly to form the flanged rim 8. The bottom of the shell 3 is slightly concaved as shown in Fig. 2, and the spring-plate 6, illustrated in Fig. 5, consists of a flat disk of sheet- 70 metal adapted to fit within the rim of the shell in spaced relation to the concaved bottom thereof. That is to say, the disk or spring-plate 6 bears against the shell 3 only at its edge and is clear of the bottom thereof to adapt it to flex downwardly as shown in Figs. 2 and 3.

The hinge-plate 4 is likewise constructed from a circular disk of sheet-metal and is provided with a slot-like opening 10 extending radially from its center. On either side of the opening 10 the plate 4 is formed with arcuate ears or hinge-sockets 11 struck up from the metal of the plate. Outwardly beyond the ears or sockets 11 the plate 4 85 is provided with raised abutments or swellings 12 which provide reinforcements or stiffening ribs for the ears 11, and also serve for another purpose as later explained. Between the abutments 12 the bridge-portion of the plate 4 is in the same plane as the main part of the plate, see Figs. 2 and 90 3. The plate 4 is also provided with an upwardly standing, circular rib 14 formed by striking up the metal in arcuate contour, the purpose of the same being to stiffen the plate to prevent it from buckling.

At a point opposite from the hinge-sockets 11 the edge of the plate 4 is sheared to form two pointed prongs 15 which are bent upwardly to adapt them to cooperate with the lever 5 to grip the neckband of the garment held therebetween.

The lever 5 consists of a strip of sheet-metal having its upper end of oval contour 110

and provided with a reduced shank at 16, the lower portion of which is bent at right-angles to form a rest 17. The sides of the rest 17 are formed with integral lateral projections 18 which serve as hinge-pins or trunnions for pivoting the lever 5 in the sockets 11 of the hinge-plate 4. At the end of the rest 17 is a curved lug or finger 19 which bears against the top of the spring-plate 6 to control the turning-action of the lever 5.

The several parts of the device are assembled to form the finished button in the manner as next explained: The spring-plate 6 is first placed in the shell 3, in the position shown in Fig. 2, and after the lever 5 has been assembled with the hinge-plate 4 by placing its trunnions 18 in the sockets 11, the hinge-plate 4 is set in the shell 3 overlying the spring-plate 6. The flanged rim 8 of the shell 3 is then rolled or swaged over the edge of the hinge-plate 4 to unite the parts in cooperative relation, the whole button being thus completed without soldering or riveting.

Figs. 1 and 2 illustrate the button with its clamp or lever 5 in open position and to apply it to use the oval head of the lever is inserted through the buttonholes of the neckband and collar, after which the lever is pressed downwardly into the position shown in Fig. 3. As the lever 5 is turned down against the back of the button its curved lug or finger 19 rides across the upper face of the spring-plate 6 and flexes the latter to a concaved form whereby its tension acts to hold the lever in closed relation. In this latter position the lever 5 clamps the collar and neckband against the sharp-pointed prongs 15 of the hinge-plate 4, thus tending to hold the collar firmly in place while preventing the button from riding up in the buttonhole and from sliding laterally thereof. The lever 5 sits substantially flat against the collar without protruding outwardly therefrom and hence the improved button will not catch in the other

garments of the wearer or cause the coat collar to bulge or hang away at the rear.

To release the clamp or lever 5 it is only necessary to insert the finger under its outer end and to tilt it upwardly, whereupon the button is easily removed from the collar and neckband. As the lever 5 is tilted back to open position its finger 19 again rides over the face of the spring-plate 6 and the spring action of the latter causes the lever to be held upright with its bent rest-portion 17 seated against the flat top of the hinge-plate 4 between the raised abutments 12. The opposite, parallel shoulders of the abutments 12 bear against the sides of the rest 17 to prevent it from being skewed out of alignment and serve as a brace or reinforcement for the lever 5 to hold it rigidly in open position whereby it resists side pressure tending to cramp it on its hinges. My improved button therefore has greater strength and staunchness than the usual device of this type and is consequently more efficient in operation and more durable in use.

Having now described the structure and arrangement of my improved button and explained the nature of the improvement, I claim:

An article of the type specified comprising a back-plate, a hinge-plate secured thereto and formed with a central opening having upstanding socketed ears on its sides and raised abutments extending rearwardly from said ears toward the edge of the plate to provide opposite parallel shoulders on the upper face of the plate, and an L-shaped lever having a rest-portion provided with trunnions pivoted in the ears on the hinge-plate, said lever adapted to be closed against the hinge-plate and to be tilted into upright position in relation thereto, the rest on said lever being arranged to sit flat against the top of the hinge-plate with its sides confined between the opposite shoulders of the abutments thereon.

In testimony whereof I affix my signature,
SAMUEL BLACHER.
